*Albert Spencer, inventor
C. L. Basile
W. T. Baugh*

UNITED STATES PATENT OFFICE.

ALBERT SPENCER, OF NEW YORK, N. Y.

MACHINE FOR SIZING HAT-BODIES.

Specification of Letters Patent No. 14,521, dated March 25, 1856.

To all whom it may concern:

Be it known that I, ALBERT SPENCER, of the city, county, and State of New York, have invented certain new and useful Im-
5 provements in Machinery for Sizing Hat-
Bodies; and I do hereby declare the following
ing to be a full description of the same.

My invention consists in giving to the
rubber board (in the hat-felting machine
10 patented to Phineas Emmons on the 24th
day of July 1855, a slight vibratory motion
when used in combination with the disk
wheel in the Emmons machine, and consti-
15 tuting an improvement thereon. But to de-
scribe my invention more particularly I will
refer to the accompanying drawing form-
ing a part of this specification, the same let-
ters of reference wherever they occur refer-
ring to like parts.

20 Figure 1, is a vertical side view of the
machine. Fig. 2 is a plan view of the same.
Fig. 3 is a transverse cut section of the
machine through the line α , α Fig. 1. Figs. 4
and 5, are representations of a face and plan
25 view of the rubber board.

Letter A, is the frame of the machine hav-
ing a trough B, in one end of it. In this
trough is arranged in a vertical position,
(on an axis C) a disk or wheel D, having its
30 face channeled with ribs radiating from the
center outward. The object of this is to roll
and carry the hat body forward through the
machine. This wheel is arranged so as to
be adjustable and apply an elastic pressure
35 on the hat body, by means of the axis C,
on which it is secured working in loose or
sliding boxes, and operated by a weighted
bell crank lever E. This lever is secured
40 to the frame of the machine, and by its
forked upper arm connecting with the end
of the axis C, so that the weight F, accord-
ing to its position on the long arm of the
lever E, will always cause the wheel to press
45 upon the hat with an elastic pressure.

45 Letter G, is the rubber board. This is
made with a gradually increasing throat
or pitch of face (as seen at g^2 , Fig. 5.) The
object of this is to form a throatway, at one
50 side of the wheel for the introduction of
the roll of felt between the opposing faces
of the wheel and rubber board. The face of
this rubber board is also ribbed like the face

of the wheel, at the center point of the rub-
ber board is an axis H, having one end se-
cured into the frame of the machine, and 55
upon which the rubber board vibrates. To
one edge of the rubber board is an ear piece
J, into which the pin K, of the vibratory
lever L, is secured. This vibratory lever is
secured by a center pin M, to the frame of 60
the machine, having one end secured to the
rubber board, and the other resting or work-
ing upon a tapis wheel N, secured upon the
axis C, so that as the axis C, rotates, it
causes a constant vibratory motion of the 65
rubber board, and thereby causes the hat
body to "size" or felt up, by a species of
working operation analogous to hand siz-
ing or felting up hat bodies. To the back
70 of the lever L, is a spring P, the object of
which is to hold the tail of the lever L,
upon the tapis wheel to keep it in position
while rotating. It will be obvious that this
precise mode of arranging the tapis and 75
lever for vibrating the rubber board may
be varied by substituting a crank or cam
motion, but as these would be but mere
changes of the application of one well known
equivalent device for that of another I do
not deem it essential that I should under-
80 take to describe them, as I claim that my
invention would cover any such substitu-
tion of devices in combination with the
wheel, for giving a vibratory motion to the
rubber board.

Having now described my invention and
its operation I will proceed to state what
I claim and desire to secure by Letters Pat-
ent of the United States:—

The disk wheel having been patented, I 90
disclaim the use of it irrespective of my com-
bination, and therefore limit myself to the
combination as hereinbefore set forth.

What I claim therefore is—

The application and use of the combina-
tion of the disk wheel and the rubber bed,
when the bed receives a vibratory motion
substantially in the manner and for the pur-
poses hereinbefore described.

ALBERT SPENCER.
